(57) **CLAIM**

The ornamental design for a cat climbing frame, as shown and described.

DESCRIPTION

FIG. 1 is a front elevational view of a cat climbing frame showing my new design;

FIG. 2 is a rear elevational view thereof;

FIG. 3 is a left elevational view thereof;

FIG. 4 is a right side view thereof;

FIG. 5 is a top plan view thereof;

FIG. 6 is a bottom plan view thereof;

FIG. 7 is a perspective view thereof;

FIG. 8 is a bottom perspective view thereof; and,

FIG. 9 is a partial enlarged view of FIG. 8.

All other broken lines in the drawings illustrate cutaways for the enlarged views that form no part of the claimed design.
